UNITED STATES PATENT OFFICE.

HERMANN ABELE, OF ZURICH, SWITZERLAND, ASSIGNOR TO OTTO FELIX FIERTZ, OF
ZURICH, SWITZERLAND.

BUNDLING-PRESS.

Specification of Letters Patent. Patented June 10, 1919.

1,306,571.

Application filed August 2, 1916. Serial No. 112,729.

To all whom it may concern:

Be it known that I, HERMANN ABELE, a citizen of Germany, residing at Zurich, Canton Zurich, Switzerland, have invented a new and useful Bundling-Press, of which

5 the following is a specification.
This invention relates to a bundling press which is characterized by having an operating footlever articulated to a toothed rack 10 which by means of a coupling is connected with a movable plate rigidly attached to rods capped with compressing trays which move toward stationary compressing trays fixed to socket-tubes on the top-plate of the 15 press arranged in such a manner that the material compressed between said movable and the stationary trays can easily be tied crosswise.

The invention is shown in the accompanying drawings to which reference will be had hereinafter and in which:

Figure 1 is a section on the line A—B of Fig. 3; Fig. 2, a plan showing the position and arrangement of the compressing rods 25 and trays which latter provide rear and side cheeks for safeguarding a bundle for compressing and allowing same to be tied crosswise; Fig. 3, a top-view with the upper plate of the press removed; Fig. 4, a section on the 30 line C—D of Fig. 1 showing the connecting table with coupling mechanism; Fig. 5, a section on the line E—F of Fig. 1. Figs. 6 and 7, being details hereinafter referred to. Fig. 6^a is a top view of Fig. 6, and Fig. 7^a

35 is a face view of Fig. 7.
The top plate 1 carries four socket-tubes 2 which carry compressing trays 3 for supporting the bundles to be compressed and 40 ported, and which trays form guides for vertically moving compressing rods 4. The rods 4 carry capping trays 5 corresponding to the trays 3 in form and position, see Fig. 2.

The lower ends of the rods 4 are fixed in a connecting table 6 through which passes 45 a vertically movable twin toothed rack 7 which has its upper end articulated to the footlever 8, while the upper end of the rack is guided by two pins 9 and 9^a.

For compressing a bundle, the footlever 50 draws the rack 7 downward, the latter drawing the rods 4 down when the connecting table 6 is coupled with the rack by means of two slotted slides 10 which can engage in the rack for the purpose and which can be 55 disengaged therefrom. Two springs 11 urge

the slides 10 toward each other so as to cause same to enter the teeth of the rack, while uncoupling is effected by means of a pair of balance levers 12 and 12^a fulcrumed on the table 6 and pin-jointed to links 13 for simultaneous motion which is imparted by a square spindle 14 engaged in the lever 12 and passing through the table 6, see Figs. 1 and 4. The spindle 14 is suspended in a bearing 15 beneath the top-plate 1 and is 60 there, by means of links 16, connected to a reversing lever 17. By suitably operating the lever 17 and engaging same in a hook or catch 18 the spindle is caused to turn so as to bring the levers 12 to an approximately 65 parallel position with the slides 10, whereby they are made to close against and engage in the teeth of the rack 7. Figs. 6 and 6^a show the lever 17 and catch 18 fitted at the under-side of the plate 1. When the lever 17 is released from the hook 18, a spring 28 pulls it so as to turn the levers 12 and 12^a in a manner so as to separate the slides 10 from the 70 rack 7.

For compressing a bundle, the footlever 8 is depressed so that the rack 7 and the table 6, being coupled, are lowered. At the same time the footlever is locked by a pawl 19 which is pivoted to said lever and engages in a twin toothed guide 20 between which the 80 footlever moves, see Figs. 1, 7 and 7^a. For removing the tied-up and fully compressed bundle from the press the rod 21, which forms a guide rod for the weight 23, is made, by its angular prolongation 22, to disengage 85 the pawl 19 in the following manner: The rod 21 is turnably mounted between two angular arms 24 and 25, and an angular upper prolongation 22^a of said rod is constrained by a spring 26 to keep in contact 90 with the reversing lever 17 and to follow the forward and rearward movements of said lever. These movements are followed by the lower portion 22 of the rod 21, thus either disengaging the pawl 19 by pressure 100 against the pin 27 (see Figs. 7 and 7^a) or leaving said pawl to the pressure of its spring.

The combined action of the various parts for compressing is as follows:—

In the idle position of the press, the rack 7 is uncoupled and the weight 23, which is suspended over rollers 31 and 32 by a rope secured to the middle of the table 6, has raised the latter with the compressing rods 110

4; the weight being slightly heavier than the last named parts.

After a bundle has been introduced between the movable capping trays and the stationary compressing trays, the rods 4 are lowered by hand pressure until the capping trays rest on the bundle, and the lever is then drawn into the hook 18. By the movement of the lever 17 the table becomes coupled to the rack 7 so that, by depressing the footlever 8, the rack 7, table 6 and rods 4 are lowered. At the movement of the lever 17, the prolongations 22 and 22^a of the spindle 21 move so that the pawl 19 is free to engage in the teeth of the guide 20 and lock the press.

For withdrawing the tied-up bundle, the reversing lever 17 is released from the hook 18 and is then drawn about half-way back 20 by its spring 28 till the levers 12 and 12^a, which have a certain amount of play between the slides 10, come into contact with the slides. By moving the lever 17, the prolongations 22 and 22^a turn around so that the prolongation 22 is brought in contact with the pin 27 of the pawl. Through the early contact of the prolongation 22 with the pawl 19 there occurs a certain space between the reversing lever 17 and the upper prolongation 22^a. As soon as the pressure on the footlever 8 releases the pawl 19, the prolongation 22^a completes its turn until it comes against the lever 17 and at this moment it causes the lower prolongation 22 to so act against the pin 27 as to disengage the pawl 19 from the teeth of the guide 20. The footlever 8 is now raised by its springs 33 in consequence of which the pressure from the

rack 7 on the slides 10 is released so that the spring 28 is able to pull the reversing 40 lever 17 over the remaining half of its path, thereby enabling the actuating parts of the slides 10 to completely disengage the latter from the rack 7. At this moment the weight 23 raises the compressing rods 4. 45

The hand-operations for using the press are shortly as follows:

For compressing, perform a slight lowering of the compressing rods till the capping trays 5 rest on the bundle, then pull the reversing lever into the hook and depress the footlever. 50

For releasing the tied bundle: disengage the reversing lever by pressure against its retaining hook and press on the footlever. 55

I claim:

A bundling press comprising as its operative parts a footlever in combination with a toothed rack articulated to the former, coupling mechanism for coupling the rack with a connecting table, the said table, compressing rods fixed to the table, capping trays for said rods, a top plate for the press with passage for the rods, socket-tubes fixed to the upper face of the top plate and engaging said rods, trays attached to the socket-tubes, a suspension weight, a rope fast to the weight and the said table respectively, guide pulleys for the rope, means for locking the footlever in its lower position, and means for disengaging same. 65 70

HERMANN ABELE.
